CLOTH AND A METHOD OF PRODUCING THE SAME

Theodor Wolff, Stettin, Germany

Application April 18, 1938, Serial No. 202,736

6 Claims. (Cl. 139—383)

This invention relates to a new type of cloth, more particularly for the manufacture of men's and boys' suits, and to a method of producing the same.

5 In a suit of clothes, which for the purpose of the description will be considered to comprise three parts, viz., the jacket, the waistcoat and the trousers, although the waistcoat itself is not an essential part of this combination, the disadvantage arises that the trousers, after a certain period of use, will exhibit considerable signs of wear, whilst the jacket and the waistcoat are still in a comparatively good condition, so that it is necessary either to discard the entire suit 10 or to purchase an additional pair of trousers to wear with the jacket and the waistcoat. In the majority of cases, however, the same material and the same pattern will not be obtainable, so that new trousers of a different pattern and possibly also a different material will require to take the place of the worn pair. In this way the suit 15 will considerably lose in appearance.

It is the object of the invention to overcome this drawback and to provide a new type of cloth 25 for the manufacture of men's and boys' suits, upon the use of which it can reasonably be expected that the trousers will endure, without deterioration in appearance, equally as long as the jacket or the waistcoat.

30 A further object of the invention is to provide a new type of cloth for men's and boys' suits which, when made from this cloth, will not differ in appearance from a suit of clothes made from a normal material.

35 In the manufacture of suitings it is usual for the weaver to produce a certain minimum length, say 360 yards, of each pattern or design, as although it would of course be possible in itself to produce any design in even the shortest length 40 it will be obvious that a certain minimum length is necessary to enable the material to be sold at a reasonable price.

In the reduction of the invention to practice each "design" is made up of two different kinds 45 of cloth, the one cloth being intended for the subsequent production of the jacket and waistcoat and the other for the trousers. The former is woven from threads of equal ply constituting both the warp as well as the weft, for example 50 two-cord or two-ply threads. The second cloth, however, is made up of a material having the same set of warp threads as the first piece of cloth, but in which the weft threads consist of a greater number of plies than the warp threads. 55 Thus, for example, the warp and weft threads

of the first cloth may be two-cord or two-ply threads, whilst in the second cloth the warp threads are two-cord or two-ply and the weft threads three-cord or three-ply threads. The second cloth, whilst not differing in appearance, 5 will be considerably stronger than the first cloth, and will be well adapted to withstand the additional wear imposed on the trousers of a man's or boy's suit.

In order to preserve the appearance of the cloth 10 and to ensure that the two cloths making up the one design will not differ in appearance it is necessary to select finer cords or plies for the thread of greater ply, so that the latter, despite the greater number of cords, will not be appreciably thicker than the threads of lesser ply.

In the ordinary way greater length of material will be required for the jacket and waistcoat together than for the trousers, so that if the complete length of any particular pattern 20 produced amounts to 360 yards, approximately 210 yards will be made up of threads which are equal in the weft and the warp, whilst the remaining 150 yards will comprise the second cloth in which the weft threads consist of an increased 25 number of cords or plies.

Preferably, therefore, the two different cloths will be in one continuous length, and the second cloth will follow immediately on the first cloth without a break, although if desired the two different cloths making up the one design can also be produced separately, in which connection the length of each may be increased in corresponding proportion.

Now when a cloth has been woven it is subjected to a certain finishing process before it is placed on the market. If the yarn has not been dyed previously, the cloth proceeding from the loom is first treated in a bath to remove the size or glue employed in weaving for better holding 40 the threads together, is then dyed, squeezed, rinsed in water, thereupon dried and stretched, and finally after renewed moistening is pressed and ironed on a calender. If previously dyed 45 yarn is employed the treatment is substantially the same with omission of the dyeing process. There may of course be certain modifications in this treatment dependent on the nature of the material. Whether, however, the two cloths comprising the one design in accordance with 50 the invention be produced in one piece or in separate lengths it is essential that they should be subjected to the said finishing treatment in one operation. It will be appreciated that in treating cloth in the manner described the slightest 55

variation in the treatment would be quite sufficient to impart an entirely different appearance to two lengths of cloth treated separately. Thus for example it is extremely difficult in the dyeing process alone to obtain a colour exactly corresponding to a previous shade employed, whilst variations in the washing or calendering process will also produce entirely different results.

In consequence, if the cloth destined for the jacket and the waistcoat and that for the trousers were subjected to separate finishing treatments, they would in all probability exhibit considerable differences in appearance despite the fact that no difference in itself is in any way apparent 15 from the use of different yarns.

The invention, therefore, covers not only the production of cloth of any particular design in the form of two distinct cloths, in which the weft threads of the one cloth differ from the weft 20 threads of the other cloth, but also the step which consists in subjecting the two cloths thus produced to a common finishing treatment.

If the two cloths are produced in one single length, they will preferably be passed as such 25 through the treatment apparatus, or if they are produced separately, they may be connected together at the ends to pass through the apparatus as a continuous web.

The invention is illustrated by way of example 30 in the accompanying drawing, in which

Fig. 1 illustrates a piece of cloth, in which the warp and weft threads are of equal ply.

Fig. 2 illustrates a piece of cloth, in which the weft threads comprise a larger number of cords 35 or plies than the warp threads.

Fig. 3 illustrates diagrammatically a finishing apparatus for the treatment of the cloth following the weaving process.

In Fig. 1 the warp threads 1 and the weft 40 threads 2 are two-cord threads. This cloth is used for producing the jacket and the waistcoat of a man's or boy's suit. In Fig. 2 the warp threads 1a are two-cord threads and the weft threads 2a are three-cord threads. The cloth 45 according to Fig. 2 is used for producing the trousers of a man's or boy's suit, the jacket and/or waistcoat of which are made from a cloth according to Fig. 1.

There is no limitation to two-cord and three-50 cord threads, and the warp threads may be, say, two-cord or two-ply threads and the weft threads four-cord or four-ply threads, or the warp threads may be three-cord or three-ply threads and the weft threads four-cord or five-cord 55 threads, and so forth, the essential feature being that the weft threads of the cloth according to Fig. 2 possess a greater number of cords than the weft threads in Fig. 1.

The weaving itself occurs in the conventional 60 fashion, there being used either dyed or undyed yarn. In either case a certain length of cloth is woven in accordance with Fig. 1, having equally corded threads in the warp and the weft, and then a further length in accordance with Fig. 2 in which the weft threads comprise a greater number of cords or plies. In the cloth according to Fig. 2 finer cords will be employed for the yarn of greater ply, so that after the 65 twisting the three-cord or three-ply yarn will not be substantially thicker than the two-ply yarn.

In a preferred embodiment of the invention, assuming for example that a total length of, 70 say, 360 yards is produced in any particular de-

sign, rather more than one-half of this length, say 210 yards, is produced in accordance with Fig. 1, whereupon the weft threads are replaced by others of the same colour, but of greater ply, and weaving is continued to the end.

If a sufficient length of cloth of each design is being produced, it may also be found convenient to produce separately the two cloths of which each design according to the invention is composed.

In either case, however, the two different cloths making up the one design are subjected to a common finishing treatment, for example in an apparatus as illustrated in Fig. 3.

After leaving the loom the cloth is conducted 15 to a suitable bath or trough 3 for removal of the size or glue employed for the weaving process for better holding the threads together. From the bath 3 the cloth passes to the dyeing vat 4, and thence to a rinsing bath 5. Upon leaving 20 the bath 5 it passes between rollers 6 for the removal of superfluous moisture, and then to a drier 7 and a steaming or conditioning apparatus 8. After leaving the latter it is suitably moistened at 9 and then passes to the calender 10, 25 being finally wound on the drum 11. If previously dyed yarn has been employed in weaving the cloth, the treatment is substantially the same with omission of the dyeing process.

Assuming the two appertaining cloths of the 30 one design have been produced in one length, the complete web of material will be passed as such through the said apparatus. If, however, they have been produced separately, they can be connected end to end and then conveyed through 35 the apparatus, or they can also be treated simultaneously as separate lengths. Whichever method is adapted, it will be obvious that both cloths will have a completely uniform appearance throughout.

What I claim as new and desire to secure by Letters Patent is:

1. Steps in a method of producing cloth for suits of clothes all parts of which present substantially identical design, appearance, and finish, while varying in strength, comprising weaving the cloth in a plurality of sections having the same set of warp threads throughout said sections, by weaving one section with weft threads of equal ply with said warp threads, weaving another section with weft threads of a greater number of plies than said warp threads and of a greater number of plies than the weft threads of the first mentioned section, all of said threads having substantially the same thickness or diameter, and subjecting the sections substantially simultaneously to the same washing and finishing treatments in substantially one operation.

2. Steps in a method of producing cloth for suits of clothes all parts of which present substantially identical design, appearance, and finish, while varying in strength, comprising weaving the cloth in a single continuous length comprising a plurality of sections and having the same set of warp threads throughout said length, by weaving one section of said continuous length with weft threads of equal ply with said warp threads, weaving another section of said continuous length with weft threads of a greater number of plies than said warp threads and of a greater number of plies than the weft threads of the first mentioned section, all of said threads having substantially the same thickness or diameter, and subjecting the sections of said continuous length of cloth substantially simultaneously to the same

washing and finishing treatments in substantially one operation.

3. As a new article of manufacture, cloth in a plurality of sections of substantially identical design and appearance for making suits of clothes, said cloth sections having the same set of warp threads, one section for making the jacket or waistcoat having weft threads of equal ply with said warp threads, and the other section as for making the trousers having weft threads of a greater number of plies than said warp threads and of a greater number of plies than the weft threads of the first mentioned section, all of said threads having substantially the same thickness or diameter, the sections having substantially identical appearance and finish and having been subjected substantially simultaneously to the same washing and finishing treatments in substantially one operation.
5. As a new article of manufacture, cloth in a plurality of sections of substantially identical design and appearance for making suits of clothes, said cloth sections having the same set of warp threads, one section for making the jacket or
10. As a new article of manufacture, cloth in a plurality of sections of substantially identical design and appearance for making suits of clothes, said cloth sections having the same set of warp threads, one section for making the jacket or
15. As a new article of manufacture, cloth in a plurality of sections of substantially identical design and appearance for making suits of clothes, said cloth sections having the same set of warp threads, one section for making the jacket or
20. As a new article of manufacture, a continuous length of cloth in a plurality of sections of substantially identical design and appearance for making suits of clothes, said cloth sections of said continuous length having the same set of warp threads, one section for making the jacket or
25. As a new article of manufacture, a continuous length of cloth in a plurality of sections of substantially identical design and appearance for making suits of clothes, said cloth sections of said continuous length having the same set of warp threads, one section for making the jacket or

waistcoat having weft threads of equal ply with said warp threads, and the other section as for making the trousers having weft threads of a greater number of plies than said warp threads and of a greater number of plies than the weft threads of the first mentioned section, all of said threads of said continuous length having substantially the same thickness or diameter, the sections of said continuous length having substantially identical appearance and finish and having been subjected substantially simultaneously to the same washing and finishing treatments in substantially one operation.

5. As a new article of manufacture, cloth for suits of clothes all parts of which present substantially identical design, appearance, and finish, while varying in strength, made according to the method of claim 1.

6. As a new article of manufacture, cloth for suits of clothes all parts of which present substantially identical design, appearance, and finish, while varying in strength, made according to the method of claim 2.

THEODOR WOLFF.
